UNITED STATES PATENT OFFICE

HENRY S. LOCKWOOD, OF SOUTH NORWALK, CONNECTICUT.

CYLINDER-LOCK.

SPECIFICATION forming part of Letters Patent No. 659,483, dated October 9, 1900.

Application filed April 24, 1900. Serial No. 14,108. (No model.)

To all whom it may concern:

Be it known that I, HENRY S. LOCKWOOD, a citizen of the United States, residing at South Norwalk, county of Fairfield, State of Connecticut, have invented a new and useful Cylinder-Lock, of which the following is a specification.

My invention relates to the class of locks commonly known as "cylinder-locks," and 10 has for its object to provide a mode of attaching the "locking-cylinders," so called, or tumbler cases to the lock-eases that will not only reduce the cost of construction, but will enable the tumbler-case to be fitted closely to 15 the door in all cases no matter how much the thickness of doors may vary, will render it impossible for the tumbler-case to be turned out, and, furthermore, will accomplish these 20 results without the use of locking-grooves, either longitudinal or circumferential.

With these ends in view my invention consists in the novel construction which I will now describe, referring to the accompanying drawings, forming part of this specification, 25 and using reference characters to designate the several parts.

Figure 1 is an elevation, partly broken away, showing my novel lock in place in a door; Fig. 2, a transverse section through the 30 edge of a door and through the lock-case and tumbler-case of a lock, the locking mechanism being omitted, as it forms no portion of my present invention; Fig. 3, a view of the upper portion of one of the side plates of a 35 lock-case detached; Fig. 4, a sectional view of the lock-case on the line 4-4 in Fig. 2, the tumbler-case and escutcheon-ring being removed; and Fig. 5 is a rear elevation of the tumbler-case detached.

40 A denotes a door; B, a lock-case having the usual face-plate 10 and removable side plate 11; C, the tumbler-case, having the usual flange 12; D, the hub, and E an escutcheon-ring.

45 The gist of my invention lies in making the tumbler-case and the corresponding openings in the lock-case which receive it of such shape relatively to each other that the tumbler-case when in engagement with the opening cannot 50 be rotated and in providing the tumbler-case on opposite sides with inclines, one of which is adapted to be engaged by a retaining-slide

to lock the tumbler-case against withdrawal. It will of course be apparent that there is practically no limit to the variations that may be made in the shape of the tumbler-case and still the same result be obtained. For example, the tumbler-case may be made triangular, 55 hexagonal, or of any polygonal form in cross-section, or it may be provided with one or 60 more sides, not necessarily flat, or with one or more projections or depressions, the opening in the lock-case of course corresponding with the configuration of the tumbler-case in cross-section. 65

I can best define the scope of my invention so far as relates to the shape of the tumbler-case by saying that it may be of any form other than circular in cross-section. In the present instance I have shown the tumbler-case as provided with two parallel sides, 70 which I have indicated by 13, and with inclines 14, diametrically opposite to each other, (so as to make the tumbler-case reversible,) said inclines being highest at the inner end 75 of the tumbler-case and running out in the sides thereof. 15 denotes the tumbler-case openings in the lock-case, which, as already stated, correspond in outline with the cross-section of the tumbler-case to such an extent 80 as to hold the tumbler-case against rotary movement. It should be understood, however, that correspondence in outline of the entire circumference of the openings with the tumbler-case is unimportant. 85

16 and 17 denote slots leading from openings 15, which in assembling receive the inclines 14 upon the tumbler-case. These slots need not correspond in shape with the inclines, it being simply necessary that the slots be large 90 enough to receive the inclines.

18 denotes a retaining-slide, (bifurcated to make the tumbler-case reversible,) the forward ends of which are preferably, though not necessarily, beveled, as at 19, to correspond with the inclines upon the tumbler-case. Suitable ways are of course provided in the side plates of the case to hold the retaining-slide in place. In the present instance I have shown slots 17 as elongated in 95 the direction of the face-plate and undercut, as at 20, and have shown the inner ends of the arms of the retaining-slide as shaped to correspond therewith, as will be clearly un- 100

derstood from Fig. 4 in connection with the other figures of the drawings. The retaining-slide may be operated to grip or release the tumbler-case in any ordinary or preferred manner. In the present instance I have shown the retaining-slide as operated by means of an adjusting-screw 21, which passes through a lug 22, projecting from the case and whose head lies in an opening 23 in the face-plate and is provided with an operating-slot 24. The portion of the adjusting-screw which passes through lug 22 is provided with a groove, (see dotted lines, Figs. 1 and 2,) which is engaged by a pin 25, passing through the lug. This pin holds the adjusting-screw against longitudinal movement, so that the retaining-slide will be moved in or out when the adjusting-screw is rotated.

In use in order to provide for great variation in the thickness of doors, escutcheon-rings of different heights may be provided. The lock-case is mortised into the door in the usual manner and a hole bored in one side for the insertion of the tumbler-case. The operation of attaching the tumbler-case to the lock-case is by my novel invention reduced to absolute simplicity and accuracy. The operator passes the tumbler-case through an escutcheon-ring, inserts the inner end of the tumbler-case into opening 15 in the lock-case, inclines 14 being in engagement with slots 16 and 17, and pushes the tumbler-case in until the escutcheon-ring lies against the face of the door, as clearly shown in Fig. 2. The retaining-slide is then moved inward until the forward end thereof engages the incline 14 on the tumbler-case. This engagement of the retaining-slide with the incline tends to

draw the tumbler-case inward slightly, so that the escutcheon-ring will engage the door 40 closely, forces the opposite side of the tumbler-case against the side of opening 15, as will be clearly understood from Figs. 2 and 3, and renders it impossible for the tumbler-case to be forced out or to be rotated under 45 any circumstances.

Having thus described my invention, I claim—

1. In a lock the combination with a tumbler-case of other form than circular in cross- 50 section and having an incline highest at the inner end and running out in the side thereof, of a lock-case having an opening corresponding in shape with the tumbler-case so as to prevent the latter from turning and a 55 retaining-slide adapted to engage the incline to lock the tumbler-case against withdrawal.

2. In a lock the combination with a tumbler-case of other form than circular in cross- 60 section and having an incline highest at the inner end and running out in the side thereof, of a lock-case having an opening with a slot leading therefrom which receives the incline and a retaining-slide adapted to engage the incline, substantially as and for the purposes set forth.

3. The lock-case B having tumbler-case opening 15 and slots 16 and 17 leading therefrom, said slot 17 being undercut as at 20, substantially as shown, for the purpose specified. 70

In testimony whereof I affix my signature in presence of two witnesses.

HENRY S. LOCKWOOD.
